UNITED STATES PATENT OFFICE.

HERMANN JOEST, OF HANOVER, GERMANY.

MANUFACTURE OF TABLE KNIVES, FORKS, OR SIMILAR ARTICLES.

SPECIFICATION forming part of Letters Patent No. 730,921, dated June 16, 1903.

Application filed May 10, 1902. Serial No. 106,800. (No model.)

To all whom it may concern:

Be it known that I, HERMANN JOEST, manufacturer, a subject of the German Emperor, and a resident of Hanover, in the Empire of Germany, have invented certain new and useful Improvements in the Manufacture of Table-Knives, Forks, or Similar Articles, of which the following is a full, clear, and exact description.

10 This invention relates to improvements in the manufacture of table-knives, forks, and similar articles; and the object is to connect the tang throughout its entire length, or nearly so, with the handle and at the same time anchor it in the same, so as to protect both tang and handle against the entrance of liquid and render them immune to the effects of acid liquids or vapors. This object is completely attained by casting around the tang of the

15 knife or fork or other like implement in a suitable mold an alloy of aluminium and magnesium, (magnalium.) This alloy closely adheres to iron or steel, behaving toward the latter like a solder, so that the iron or steel tang becomes a part of the handle.

The annexed drawings illustrate two forms of the invention in connection with a table-knife.

Figure 1 is an elevation of the knife with the handle in section; Fig. 2, a section of Fig. 1 on the line A B, and Fig. 3 another form of the knife with another form of tang.

Around the suitably-fashioned tang *a*, of iron or steel, which extends practically through the entire length of the handle, an alloy of aluminium and magnesium (magnalium) is cast in a mold corresponding in size and shape to the handle in such a manner that the casting *b*, which intimately combines to an integral whole with the tang *a*, itself forms the handle, the latter therefore requiring no further covering or inclosure. The shape of the tang is so chosen as to produce the best possible anchoring with

the metal cast around it. Cast handles of magnalium produced in this manner, which 45 can only be removed by force from the tangs, are very convenient, absolutely acid-proof, do not oxidize, and can be plated with silver or other metal without difficulty.

When the article provided with the handle 50 becomes useless, the metal cast around the tang can be easily removed by melting and used again.

When the handle described is used for table-knives, the butt *c* of the blade is preferably cast in as well in the manner shown in the drawings, the connection of the handle with the blade being thus strengthened, the appearance of the knife improved, and the entrance of liquid between the tang and the 60 handle rendered impossible.

What I claim, and desire to secure by Letters Patent, is—

1. A table-knife or other similar article provided with a handle of aluminium-magnesium 55 alloy cast around the iron or steel tang and butt and thus united with the same, substantially as described.

2. A table-knife or similar article provided with a handle of aluminium-magnesium alloy 70 anchored to and united with the iron or steel tang throughout its whole length by casting, substantially as described.

3. A table-knife or similar article having an iron or steel tang provided with projections, 75 and a handle formed by an alloy of aluminium and magnesium (magnalium) cast around said tang and having interlocking engagement with the projections thereof.

In testimony whereof I have signed my name 80 to this specification in the presence of two subscribing witnesses.

HERMANN JOEST.
